COMBINATION DENTIFRICE DISPENSER AND
TOOTHBRUSH SUPPORTING MEANS

Harold C. Blankenbiller, East Hampton, Conn.

Application December 2, 1949, Serial No. 130,713

4 Claims. (Cl. 222—126)

1

The present invention relates in general to dispensing devices and more especially to an improved container for dispensing powdered dentifrice, the invention pertaining in particular to toothbrush-supporting means cooperatively associated with valve-means for delivering a quantity of powdered dentifrice onto the toothbrush.

An object of the invention is to provide a superior container for dispensing a powdered dentifrice.

A further object of the invention is to provide a dentifrice-dispensing container having toothbrush-supporting means and valve-means of durable and economical construction and characterized by ease and convenience of operation, whereby a powdered dentifrice may be delivered in a proper quantity onto a toothbrush without the liability of the powder being spilled and wasted, and also without the liability of the powder being wetted and deteriorated by the brush when the latter is wet.

A still further object of the invention is to provide a superior container for dispensing a powdered dentifrice wherein improved toothbrush-supporting means is used in conjunction with superior valve-means for delivering a measured quantity of powdered dentifrice onto the toothbrush.

A still further object of the invention is to provide a tooth-powder dispensing-container with superior valve-means for delivering the dentifrice from the container onto a toothbrush.

Other objects and advantages will appear to those skilled in the art from the following, considered in conjunction with the accompanying drawings.

In the accompanying drawings, in which certain modes of carrying out the present invention are shown for illustrative purposes:

Fig. 1 is a front end elevation of a container for powdered dentifrice embodying the improved valve-means and toothbrush-supporting means of this invention;

Fig. 2 is a side elevation partly in section of the dentifrice container of Fig. 1 showing the end-closure provided with the improved valve-means and toothbrush-supporting means of this invention;

Fig. 3 is a view similar to Fig. 2 but shows the sleeve-valve of the valve-means displaced for dispensing a quantity of powdered dentifrice onto a toothbrush;

Fig. 4 is an end elevation in section on line 4—4 of Fig. 3 showing the arrangement of the valve-spring and valve-spring supporting-bracket;

2

Fig. 5 is an enlarged end elevation in section on line 5—5 of Fig. 3 showing details of the construction of the valve-means of the dispenser; and

Fig. 6 is a perspective view of the sleeve-valve of the dispenser including a modified valve-spring.

Referring to the drawings, the container for the powdered dentifrice is indicated generally at 10 and comprises preferably a conventional can formed of metal or an equivalent material and of elliptical shape in cross section, although any other cross section may be used. One end of the can is provided with a permanent end wall 11, while the opposite end of the can is provided with a removable end-closure 12 which comprises a substantially-elliptical cover having a peripheral flange 13 at substantially right angles thereto arranged to telescope over the open end of the can and to be held thereon by frictional engagement therewith.

Formed integrally with the cover or end-closure 12 of the can is brush-supporting means indicated generally at 14 and comprising a lip struck up or otherwise formed from the end-closure 12 immediately adjacent the bottom edge thereof, the lip 14 being a hollow protuberance substantially U-shaped in cross section, as shown especially well in Figs. 2 and 3, and conforming on its underside to the profile of the bottom edge of the end-closure 12. As shown in Fig. 1, the lip is substantially symmetrical with respect to the major axis of the end-closure and is provided with an upper toothbrush-supporting surface 15 which is substantially flat, substantially perpendicular to the plane of the end-closure, and extends substantially transversely of the major axis thereof.

Although the hollow lip construction is preferred from the standpoint of economy of construction, it will be understood that the brush-supporting lip 14 may be formed as a separate element, either hollow or solid, and fastened to the end-closure by welding, soldering or equivalent means.

Mounted at the opposite end of the end-closure 12 of the container substantially symmetrical with respect to its major axis and perpendicular to the end-closure 12, is improved valve-means 16 adapted to be used in conjunction with the brush-supporting lip for delivering a quantity of powdered dentifrice onto a toothbrush supported thereon, as indicated by broken lines in Figs. 1, 2 and 3. The valve-means 16 is shown especially well in Figs. 2 and 3 and comprises a cylindrical

sleeve 17 adapted to engage at its inner end in an aperture 18 of corresponding dimensions in the end-closure 12 of the container; and to be fixedly secured in the aperture 18 by fastening-means which, in the embodiment shown, comprises an annular bead 19 having a bearing against the outer surface of the end-closure 12; and an inner annular flange 20 turned over on the inner surface of the end-closure 12. Although this construction is preferred in the interest of economy and rigidity of construction, it will be appreciated that the sleeve 17 may be welded to the end-closure 12 in its aperture 18, or formed integrally with the end-closure by a deep-draw process.

The outer end of the sleeve 17 is provided with an annular internal flange 21 bent at substantially right angles to the side walls of the sleeve and constituting stop-means for the sleeve-valve hereinafter described, the central opening defined by the annular flange 21 constituting a guide-aperture 22 for the sleeve-valve. Formed in the bottom side wall of the sleeve 17 adjacent the end wall 12 of the container, is an elongated discharge-port 23, the longitudinal axis of which extends substantially transversely of the major axis of the end-closure 12.

Mounted within the sleeve 17 for reciprocable movement therein, is a sleeve-valve indicated generally at 24 comprising a cylindrical skirt-portion 25, and a forwardly-projecting substantially-cylindrical button-portion 26 of reduced diameter provided with an imperforate end wall 27, the button-portion 26 of the sleeve-valve being slidable in the guide-aperture 22 of the sleeve 17. The external diameter of the skirt-portion 25 of the sleeve-valve is such as to make a smooth sliding fit in the sleeve 17. Moreover, the overall length of the skirt-portion of the sleeve-valve corresponds substantially to the length of the sleeve 17, the forward end of the skirt 25 having an annular shoulder 28 at its intersection, with the button-portion 26 of the sleeve-valve arranged to abut against the annular stop-shoulder 21 of the sleeve 17.

Formed in the bottom side of the skirt-portion 25 of the sleeve-valve is an elongated aperture 29 which, in the normal operating position of the sleeve-valve, extends substantially transversely of the major axis of the end-closure 12. By reciprocating the sleeve-valve longitudinally within the sleeve 17, the aperture 29 of the sleeve-valve is adapted to be moved into registry with the discharge-port 23 of the sleeve 17 so as to permit discharge of the powdered dentifrice therefrom; and to be moved out of registry with the discharge-port 23 to close the latter.

Normally, the sleeve-valve is resiliently held in its forward or outer position in the sleeve 17, as shown in Fig. 2, whereby the aperture 29 of the sleeve-valve is out of registry with the discharge-port 23 of the sleeve, the resilient means for holding the sleeve-valve in its normal forward position comprising, in a preferred embodiment, a coil spring 30 adapted to be mounted within the sleeve-valve substantially coaxially therewith. To this end, the rear end of the coil spring 30 is adapted to engage against and to be suitably secured to the upwardly-projecting bifurcated arm 31 of a bracket 32, the lower end of which is secured in any suitable manner to the inner face of the end wall 12. The opposite or forward end of the coil spring 30 is adapted to abut against the end wall 27 of the button-portion 26

of the sleeve-valve. In this connection, the button-portion 26 of the sleeve-valve is provided with an internal bushing 33 for supporting the forward end of the coil spring 30 in coaxial relationship with the rear end thereof.

In explaining the operation of the combined toothbrush-supporting means and valve of the dispenser, let it be assumed that the can 10 contains a powdered dentifrice. Then, by swinging the can down into a substantially-horizontal position, as shown in Fig. 2, or better yet, into a somewhat downwardly-inclined position, the powdered dentifrice within the can will flow forward into and fill the sleeve-valve 24. Then, having placed the tufted portion 34 of the toothbrush upon the supporting-surface 15 of the toothbrush-supporting lip 14, the operator engages his index finger or thumb against the end wall 27 of the sleeve-valve and pushes the latter inwardly relative to the sleeve 17, thereby moving the aperture 29 of the sleeve-valve into registry with the discharge-port 23. Immediately, the powdered dentifrice within the sleeve-valve will flow out of the discharge-port 23 onto the tufts 34 of a brush supported on the brush-supporting lip 14 directly beneath the discharge-port 23. Upon releasing the button-portion 26 of the sleeve-valve, the force of the compressed spring 30 will slide the sleeve-valve forwardly in the sleeve 17, thereby moving the aperture 29 of the sleeve-valve out of registry with the discharge-port 23 of the sleeve to close the latter.

Fig. 6 of the drawings shows a modified resilient means for actuating the sleeve-valve 24, the resilient means in the modified construction comprising preferably a substantially Y-shaped leaf spring 35, the lower leg-portion 36 of which is riveted or secured in any equivalent manner to the inner face of the end-closure plate 12 of the container, while the upper transversely-spaced arms 37, 37 of the leaf spring are engaged with the rear end of the sleeve-valve at substantially diametrically-opposite points on the horizontal diameter thereof. To minimize the area of contact with the end of the sleeve-valve, the upper extremity of each arm 37 of the leaf spring is formed with an S bend to produce a substantially-semicylindrical bearing-rib 38 for engagement with the inner end of the sleeve-valve.

The improved powdered-dentifrice dispenser of this invention is thus characterized by improved valve-means cooperatively associated with a toothbrush-supporting means for supporting the tufted portion of a toothbrush directly opposite the discharge-port of the valve-means for receiving a quantity of powdered dentifrice therefrom. In that the quantity of powdered dentifrice delivered from the valve-means on opening its discharge-port corresponds substantially to the quantity of powder within the valve means, the quantity of powder delivered is a measured quantity. As indicated above, the valve-means is constructed and arranged for operation by the index finger or thumb of the hand holding the container, the toothbrush-supporting means being so disposed with respect to the valve-means that the tufts of the toothbrush do not come in contact with the powdered dentifrice to wet or deteriorate the same. The dispenser of this invention thus eliminates the necessity for pouring powder into the palm of the hand and picking it up with the wet or damp tufts of the brush.

Although the dispenser of this invention is especially suitable for dispensing a powdered

dentifrice, it will be understood that it may be used for dispensing powdered detergents and materials of a similar nature.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a container for dispensing a powdered dentifrice, the combination including: an end-closure at one end of said container; toothbrush-supporting means adjacent one edge of said end-closure, said toothbrush-supporting means being a substantially-flat element constructed and arranged to project substantially perpendicularly from the plane of said end-closure and to extend with its longitudinal axis substantially transversely of a major axis thereof; and valve-means adjacent the opposite edge of said end-closure, said valve-means being constructed and arranged to project outwardly substantially perpendicularly to the plane of said end-closure and having an elongated discharge-port directly opposite said toothbrush-supporting means, said elongated discharge-port extending substantially transversely of the said major axis of said end-closure.

2. In a container for dispensing a powdered dentifrice, the combination including: an end-closure at one end of said container; toothbrush-supporting means adjacent one edge of said end-closure, said toothbrush-supporting means comprising a substantially-flat integral lip projecting outwardly substantially perpendicularly from the plane of said end-closure and extending with its longitudinal axis substantially transversely of a major axis thereof; and manually-operated valve-means adjacent the opposite edge of said end-closure, said valve-means being constructed and arranged to project outwardly substantially perpendicularly to the plane of said end-closure and having an elongated discharge-port directly opposite said toothbrush-supporting means, said elongated discharge-port extending substantially transversely of the said major axis of said end-closure.

3. In a container for dispensing a powdered dentifrice, the combination including: an end-closure at one end of said container; toothbrush-supporting means adjacent one edge of said end-closure, said toothbrush-supporting means comprising an integral lip projecting outwardly substantially perpendicularly from the plane of said

end-closure and extending substantially transversely of a major axis thereof; and valve-means adjacent the opposite edge of said end-closure, said valve-means comprising a sleeve secured to said end-closure and projecting outwardly substantially perpendicularly to the plane thereof, said sleeve having an elongated discharge-port therein directly opposite the said toothbrush-supporting lip and extending substantially parallel thereto, a sleeve-valve having an aperture therein, said sleeve-valve being slidably mounted in said sleeve for reciprocable movement therein to move the aperture of said sleeve-valve to and from registration with the elongated discharge-port of said sleeve, and resilient means constructed and arranged normally to hold said sleeve-valve resiliently in said sleeve with the aperture of said sleeve-valve out of registry with the discharge-port of said sleeve.

4. Valve-means for a detergent-dispensing container having an end-closure provided with an aperture in communication with said container, said valve-means comprising a sleeve having a discharge-port therein, said sleeve being secured to said end-closure over the aperture thereof and substantially perpendicular to the plane of said end-closure, an annular stop-shoulder at the outer end of said sleeve, a sleeve-valve reciprocably mounted in said sleeve, said sleeve-valve having an end-wall, and an aperture in said sleeve-valve arranged to be registered with the discharge-port of said sleeve to permit discharge of the measured quantity of detergent within said valve-means therefrom and to be moved out of registry with the discharge-port of said sleeve to close said port, and resilient sleeve-valve operating-means for resiliently holding said sleeve-valve in said sleeve against the annular stop-shoulder thereof, with the aperture of said sleeve-valve out of registry with the discharge-port of said sleeve, said resilient means comprising a leaf spring secured at one end to said end-closure and engaged at its opposite end against the inner end of said sleeve-valve.
